UNITED STATES PATENT OFFICE.

SWAN F. SWANSON, OF PUEBLO, COLORADO.

STEAM-BOILER.

1,375,616.

Specification of Letters Patent. Patented Apr. 19, 1921.

Application filed June 12, 1919. Serial No. 303,563.

To all whom it may concern:

Be it known that I, SWAN F. SWANSON, a citizen of the United States, and residing at Pueblo, in the county of Pueblo and State 5 of Colorado, have invented new and useful Improvements in Steam-Boilers, of which the following is a specification.

My present invention relates to steam boilers, and particularly to a boiler adapted for 10 use on a self-propelled vehicle, and in other like connections.

An object of the invention is to provide a boiler adapted for use with a hydro-carbon burner which is compact in its arrangement 15 and which presents a maximum heating surface through a peculiar arrangement of water tubes.

A further object resides in so constructing the boiler that there is little likelihood of 20 scale forming within the water tubes to lessen the efficiency of the boiler, and in providing a mud drum into which mud and other sedimentary matter is deposited by the natural flow of water in the boiler from 25 the feed water supply.

Yet another object is to provide, in conjunction with the water tubes, a dry steam drum with a steam outlet pipe for conducting the dry steam to the place where it is to 30 be used.

With these and other objects in view, which will be apparent from the specification, drawings, and claims, this invention includes certain novel features of construction and combinations of parts which will 35 now be set forth.

In the drawings:

Figure 1 is a view in side elevation and in partial broken section of the front portion of an automobile showing my improved 40 boiler in relative position.

Fig. 2 is a view in plan, and with portions in section, illustrating the relative arrangement of the various parts of my boiler.

Fig. 3 is an end elevation of the boiler taken from the front.

Fig. 4 is a broken sectional view through the dry steam drum to better disclose the connection of the vertical water tubes there- 50 with.

Fig. 5 is a view similar to Fig. 4 illustrating the connection of the steam outlet pipe with the dry steam drum.

Fig. 6 is a detail sectional view showing 55 the connection of the primary water mani- folds and the water column with the water

distributing manifold and illustrating the fitting of the clean-out plug therefor.

Fig. 7 is a fragmentary view partly in section of the mud drum and blow-off valve. 60

As disclosed in Fig. 1, the chassis frame of an automobile is shown at 1, this frame being mounted and suspended in any approved manner to be carried by the wheels, and a hood 2, similar to the usual engine 65 hood of a gasoline propelled motor car is carried on the forward end of the frame. The hood in this instance incloses a heat insulating jacket 3, built up of asbestos sheets or other suitable material, within which the 70 boiler structure, the heating burners, and the other elements are housed.

A water distributing manifold 4 is made of a length corresponding substantially to the width intended for the completed boiler, 75 and a mud drum 5 is of the same length. Primary water manifolds 6 are fitted in openings formed along one side of said distributing manifold and have their ends upset, are brazed, welded, or are otherwise secured to be integral therewith. These primary manifolds are disposed to line in the same horizontal plane, and the free end of each manifold 6 is bent over and is connected vertically with the upper side of mud 80 drum 5, this mud drum being horizontally disposed and extending parallel with distributing manifold 4.

A plurality of vertical water tubes 7 are connected in spaced relation through the top 90 of each of the primary manifolds 6, and at their upper ends these vertical water tubes are curved and are connected with the dry steam drum 8, substantially as shown in Fig. 4. As illustrated in Figs. 1 and 3, this 95 dry steam drum is disposed above and substantially parallel with the horizontally extending water manifolds 6, and in each instance the vertical water tubes curve in to connect therewith. A steam outlet or supply pipe 9 is connected through the top of steam drum 8, as shown in Fig. 5, or at some other convenient or practical point, and this steam pipe is led to the vehicle propelling engine or to some other point 100 where the steam generated in the boiler is to be used. Suitable steam supply control valves or other mechanism for this purpose will be included in the line embracing pipe 9, but as this is not a part of my present invention such structure is not here shown. 105

A water column 10 is connected vertically

and substantially centrally with distributing manifold 4, and extending upwardly has connection with the forward end of steam drum 8. A feed water supply pipe 11 is led from a feed water pump, a gravity feed tank, or other suitable source of water supply, and is connected with water column 10 at a height corresponding substantially to the water level which it is desired to maintain in the water tubes, which level it is to be understood will in all cases be established to keep the water in the vertical extent of the several water tubes and out of the curved portions thereof.

In line with each of the primary manifolds 6, distributing manifold 4 has a clean-out opening 13, as best shown in Fig. 6, and screw plugs 14 are provided to close these openings. By reason of the fact that the water in water tubes 7 at no time rises to a level within the curved portions thereof, scale forming and other sedimentary matter will be precipitated by gravity settling into primary manifolds 6, and as the supply of feed water to these manifolds is from distributing manifold at the forward end, the wash of feed water will carry this precipitated matter toward mud drum 5 into which it will deposit by gravity through the vertically extending bent ends of primary manifolds 6.

If perchance the flow of feed water be not sufficiently strong to carry the sedimentary matter to the mud drum or if the use of foul water causes heavy precipitation, any one or each of the primary manifolds can be cleaned and even scraped by removing plug 14 closing the cleaning opening 13 in line therewith. To discharge mud and other extraneous matter trapped in drum 5 a blow-off valve 15 is connected therewith at a low point.

A suitable oil or other burner structure is provided at 16 beneath the primary manifolds 6 and fuel is piped or supplied to the burner as may be desired.

In the use of my improved boiler, with all of the plugs 14 in place and the blow-off valve 15 closed, water is supplied through feed water pipe 11 to the desired level. The fire is now lighted under the boiler and the heat therefrom rises between primary manifolds 6, around the vertical portions of the water tubes 7, and then passes up about the dry steam drum 8 and through between the curved portions of the water tubes. As the water within the vertical tubes is heated steam is generated which rises to the curved portions of the tubes. Here the steam is further heated and it is then discharged into drum 8 as dry steam. As the water within the boiler is evaporated additional water is supplied to maintain the proper water level, and as the feed is from the forward ends of the several primary mani-

folds 6 toward the rear ends thereof which connect with the mud drum 5, sedimentary matter failing to secure depositing hold upon the vertical water tubes is precipitated into the primary manifolds and is washed rearwardly therein to deposit in drum 5. By opening blow-off valve 15, drum 5 is cleaned and mud and other precipitates are discharged therefrom.

While, in the foregoing, I have described specific embodiments of construction and use, and have mentioned only certain possible modifications, it is to be understood that in practice I do not wish to limit myself to such specific details as are herein set forth, but may resort to any practical modifications falling within the scope of the invention as defined in the appended claims.

I claim:

1. A steam boiler including with a water distributing manifold, a plurality of primary water manifolds each connected at one end with said distributing manifold and extending in parallel relation in a horizontal plane, a mud drum to which the remaining end of each of said primary manifolds is connected, a dry steam drum disposed above and parallel with said primary manifolds, and a plurality of water tubes associated with each of said primary manifolds extending vertically upwardly therefrom and each curved over at its upper end to connect with said steam drum. 85 90 95

2. A steam boiler including with a water distributing manifold, a plurality of primary water manifolds each connected at one end with said distributing manifold and extending in parallel relation in a horizontal plane, a mud drum to which the remaining end of each of said primary manifolds is connected, a dry steam drum disposed above and parallel with said primary manifolds, a plurality of water tubes associated with each of said primary manifolds extending vertically upwardly therefrom and each curved over at its upper end to connect with said steam drum, a feed water supply connection to said distributing manifold, and a blow-off valve to discharge said mud drum. 100 105 110

3. A steam boiler including with a water distributing manifold, a plurality of primary water manifolds each connected at one end with said distributing manifold and extending in parallel relation in a horizontal plane, a mud drum to which the remaining end of each of said primary manifolds is connected, a dry steam drum disposed above and parallel with said primary manifolds, a plurality of water tubes associated with each of said primary manifolds extending vertically upwardly therefrom and each connected at its upper end with said steam drum, a vertical water column connected with said steam drum and with said distributing manifold, and a feed water supply 115 120 125 130

pipe joined with said water column below the connection to said steam drum.

4. A steam boiler including with a horizontally disposed water distributing manifold, a plurality of primary water manifolds joined with said distributing manifold and lying in the same horizontal plane therewith, a plurality of vertical water tubes connected throughout the body portion of
5 each of said primary manifolds, a steam drum with which each of said vertical water tubes is connected at its upper end, said dis-

tributing manifold having openings formed therein in line with the several primary manifolds with means to close the same and 15 each of said manifolds at the remaining end being bent to extend vertically downwardly, a horizontally disposed mud drum with which the downwardly extending ends are connected, and a blow-off from said mud 20 drum.

In testimony whereof, I affix my signature.

SWAN F. SWANSON.
